PILOT BURNER APPARATUS

George A. Tuck, San Francisco, Calif.

Application April 1, 1935, Serial No. 13,997

5 Claims. (Cl. 158—117.1)

This invention relates generally to burner equipment for household heating furnaces, floor furnaces, water heaters, and like appliances, which are supplied with natural or artificial fuel gas. It is concerned primarily with apparatus utilizing a temperature-responsive element, whereby the supply of gas to the main burner is interrupted if the pilot burner becomes extinguished.

10 In apparatus of the above character it has been common in the past to utilize a bimetallic strip or like temperature-responsive element, which is associated with the pilot burner and which transmits motion to a gas control valve. 15 In some gas appliances, as for example water heaters, the valve may directly control gas supplied to a main burner, while in other appliances the valve may control an auxiliary shut-off valve which in turn controls gas supplied to the main burner. In constructions of the prior art, the control valve, which is operated by flexing of the bimetallic element, requires a packing about its operating member, to avoid leakage of gas to the atmosphere. Such a packing gland causes 20 operating difficulties, in that if it is sufficiently tight to avoid leakage to the atmosphere, the forces required for proper operation are of such magnitude as to place undue strain upon the bimetallic element, with the result that operation 25 may be unreliable or the bimetallic element may take a permanent deformation and thus require frequent adjustment or replacement.

It is an object of the present invention to afford an apparatus of the above character in which the 30 necessity of providing a packing gland about the operating member of the control valve is obviated, thereby enabling the bimetallic element to perform its functions in a reliable fashion, with operating forces of relatively small magnitude.

40 A further object of the invention is to provide an assembly, including a pilot burner and thermostatic control means, which is relatively compact and which can be placed as a unit directly in the combustion chamber of a gas appliance.

45 Additional objects of the invention will appear from the following description in which certain embodiments of the invention have been set forth in detail in conjunction with the accompanying drawing.

50 Referring to the drawing:

Fig. 1 is a side elevational view, in cross-section, illustrating a device incorporating the present invention.

55 Fig. 2 is a plan view of the device shown in Fig. 1.

Referring first to Figs. 1 and 2, the device illustrated consists of a body 10, which can be in the form of a suitable casting. Openings 11 and 12 are provided in this body, for connection with the pipes or tubes 13 and 14. Secured to the body 10, and forming in effect a part of the same, there is a fitting 16 which in turn carries a pilot burner tip 17. The opening 11, with which tube 13 connects, communicates with a chamber 18 formed in the body 10 and which will herein-after be referred to as a "gas admission chamber". The port 12 communicates with a space or chamber 19, which is separated from chamber 18 by the valve seat 21.

Fitting 16 is also formed to afford a chamber 15 22, in which fuel gas supplied to the burner tip 17 is intermixed with combustion-supporting air. This chamber is in communication with the external atmosphere through a side opening 23, and is separated from the chamber 18 by the wall 24. 10 As illustrated, wall 24 is in the form of a plug, having threaded connections with the body 10 and the fitting 16, and therefore serving to connect these parts together. Wall 24 is provided with a small plug 26, which is drilled to afford 20 a restricted orifice 27 of fixed dimensions. In order that the size of this orifice may not vary with changes in temperature, it is desirable to form the plug 26 of a metal or metal alloy having 25 a negligible coefficient of temperature expansion, 30 as for example invar.

To provide a suitable valve member for co-operating with seat 21, a metal ball 28 is provided in the chamber 18, and this ball is attached to the lower end of an operating rod or 35 wire 29. The wall 24 is provided with an opening 31, through which the rod 29 slidably extends. Since opening 31 affords a certain amount of clearance around rod 29 to facilitate substantially frictionless raising and lowering of the rod 40 to effect opening and closing movements of ball 28, a certain amount of gas leakage will occur from chamber 18 to the chamber 22, through the clearance so afforded, in addition to flow of gas 45 through the restricted orifice 27. In order that ball 28 may rest with the proper amount of pressure upon its seat 21, a suitable follower weight 33 is provided. This follower weight has a central opening 34 to accommodate rod 29, and is adapted to normally rest upon the upper side of the 50 ball 28.

In order to effect raising and lowering movements of rod 29 by externally applied forces, a lever 36 is provided. This lever extends through the opening 23 and is carried by a ful-

crum pin 37. Its inner end is attached to the upper end of rod 29, whereby when the lever is rotated in a clockwise direction as viewed in Fig. 1, the ball 28 is raised from its seat.

5 Operating forces are applied to the exterior end of operating lever 36 by thermostatic means, which can be described as follows:—Secured to the body 10 there is an extension bracket 38. Attached to the upstanding portion 39 of this 10 bracket, there is a bimetallic strip 41. The free end of this strip terminates in proximity with the burner tip 17. The discharge orifice from tip 17 has been shown in the form of a slot 42 which, on that side of the tip adjacent the free end of 15 strip 41, delivers a part of its flame on the underside of the strip to afford rapid heating of the same when the strip is cool.

Disposed below the bimetallic strip 41 there is a weighted lever 44, one end of which has a pivotal 20 connection 46 to the bracket 38. The free end of bimetallic strip 41 is provided with a slot 47, to loosely accommodate a screw 48. The lower end of the screw is shown having an adjustable threaded connection with a plate 49, which in turn 25 is attached to the free end of lever 44. Beneath plate 49, lever 44 is provided with a shoulder or ledge 51, which is adapted to engage the exterior end of lever 36.

In a typical installation, the device described 30 above is mounted in close proximity to a main burner 52, which is to be ignited by a flame from the pilot burner tip 17. To facilitate such an installation, the body 10 is shown provided with a bracket 53, which can be attached to the main 35 burner or to some other part of the heating appliance which may be conveniently afforded.

Operation of the device described above can now be explained as follows:—Pipe 13 is connected to a source of gas supply, while pipe 14 is connected to supply gas to the main burner 52. Assuming that the pilot burner is in operation, the flame from the burner tip serves to maintain the bimetallic strip 41 at an elevated temperature, so that this strip is flexed downwardly to substantially the position indicated by the dotted lines in Fig. 1. The weighted lever 44 will also assume a lowered position, as indicated by dotted lines, to maintain the exterior end of lever 36 depressed and to maintain ball 28 elevated with respect to 50 its seat. Thus, under such conditions, gas is free to flow past the valve ball 28 and through pipe 14 to the main burner. Likewise, since lever 44 is resting upon lever 36, there is no strain upon the bimetallic strip. Assuming now that the pilot 55 flame becomes extinguished during periods when the main burner 52 is not in use, bimetallic strip 41 cools and flexes upwardly to raise the weighted lever 44. Raising of lever 44 is accompanied by 60 in Fig. 1, to drop the valve ball 28 on its seat 21. Thereafter no further gas can be supplied to the main burner, until the device is recycled by again igniting flame issuing from the burner tip 17, to reheat the bimetallic strip 41.

65 A particularly novel feature of the device described above is that leakage past the rod 29 is received within the mixing chamber 22, from whence it is conveyed as part of the combustible mixture of gas and air to the burner tip 17. This 70 feature makes possible the absence of any packing about rod 29, and the absence of packing makes possible substantially frictionless operation. Thus, only small predetermined forces need 75 be applied to the outer end of lever 36, such as are afforded by lowering the weighted lever 44.

A further feature of the invention is that the strain placed upon bimetallic strip 41 is never in excess of the amount of force required to lift lever 44. Therefore the bimetallic strip is never stressed beyond its elastic limit, and it will not 5 take a permanent deformation but will maintain a given adjustment over long operation periods. As previously noted, when the bimetallic strip is heated (at which time it is more susceptible to permanent deformation by stress), no strain of 10 any kind is placed upon it, since lever 44 is carried by lever 36. Another desirable characteristic is that a compact assembly is provided which may be mounted as a unit in close proximity to the main burner. Thus, installation of the 15 device is simplified, and no extended motion transmitting members leading to remote controlling devices need be employed.

I claim:

1. In pilot burner apparatus, a gas flow control 20 valve having a projecting operating member about which gas leakage can occur, means forming a chamber entirely enclosing the projecting portion of the operating member, the chamber serving to receive the gas leakage, a burner tip 25 communicating with said chamber, an air admission port communicating between the outer atmosphere and the interior of the chamber, an actuating member connected to the projecting end of the operating member within said chamber, and extending through said opening to the exterior of the chamber, and temperature-responsive means heated by the flame of the burner tip for operating the actuating member.

2. In pilot burner apparatus of the character 35 described, a body forming a chamber for mixing air with fuel gas, a pilot burner tip communicating with the chamber, one wall of said chamber having an orifice for admitting fuel gas and another wall of the chamber having an opening for 40 admitting combustion-supporting air, a gas flow control valve member, an operating member connected to said valve member and slidably extending through said one wall and terminated with said mixing chamber, an actuating lever 45 connected to the inner end of the operating member and extending through said opening to the exterior of the body, and temperature-responsive means for operating said actuating member, said temperature-responsive means being located exteriorly of said body.

3. In pilot burner apparatus of the character described, a hollow body having an inner wall serving to divide the interior of the body into a gas admission chamber and a gas mixing chamber, a movable valve member located in the gas admission chamber, a valve operating member having its one end connected to the valve member and being slidably extending through an aperture in said wall whereby leakage of gas may 60 occur through said aperture into the gas mixing chamber, the other end of said member being disposed and enclosed within the gas mixing chamber, an air admission opening in the body leading from the exterior atmosphere to the mixing 65 chamber, a pivotally mounted actuating lever connected to the inner end of the operating member and extending to the exterior of the body through the air admission opening, an auxiliary orifice serving to admit gas from the gas 70 admission chamber to the gas mixing chamber, a burner tip communicating with the mixing chamber, and temperature-responsive mechanism located exteriorly of the body for operating said actuating member, said temperature-responsive 75

means including a bimetallic strip disposed to be heated by the flame of the burner tip.

4. In pilot burner apparatus of the character described, a hollow body having an inner wall serving to divide the interior of the body into a gas admission chamber and a gas mixing chamber, a burner tip communicating with the mixing chamber, a movable valve member in the gas admission chamber, an air admission opening in the body leading from the exterior atmosphere to the mixing chamber, an actuating member extending through said opening from the exterior of the body to the mixing chamber, a reciprocable operating member connecting the valve member with the inner end of the actuating member, said operating member being entirely enclosed by the body, there being an opening in the wall to loosely accommodate the operating member whereby gas leakage occurs from the admission chamber to the mixing chamber about said operating member, an auxiliary orifice serving to establish communication between the gas admission chamber and the gas mixing chamber, and temperature-

responsive means located exteriorly of the body for applying moving forces to the outer end of the actuating member, said temperature-responsive means including a bimetallic strip disposed to be heated by the flame from the burner tip.

5. In pilot burner apparatus of the character described, a pilot burner, valve means for controlling flow of gas to the pilot burner, an actuating member adapted to be moved in a vertical direction to effect operation of said valve means, and temperature responsive means for applying motion to said actuating member, said temperature responsive means including a bimetallic strip disposed to be heated by the flame from the burner, means forming a fixed support for one end of said strip, a weighted lever arranged to engage the actuating member to move the same in one direction, and means forming a lost motion connection between the free end of the bimetallic strip and the free end of the weighted lever, whereby when said bimetallic strip is permitted to cool, it serves to lift said weighted lever.

GEORGE A. TUCK.
